VENETIAN BLIND TILTING DEVICE

Raymond C. Pratt, Chicago, Ill., assignor to H. B. Dodge and Company, Chicago, Ill., a corporation of Illinois

Application May 10, 1934, Serial No. 724,934

17 Claims. (Cl. 156—17)

This invention relates to Venetian blinds, and particularly to a tilting cord device for use on Venetian blinds.

The primary object of the present invention is to provide a new and novel improved operating device for shifting or tilting the tilting bar of a Venetian blind.

Another object of the invention is to provide an attractive appearing tilting cord device which is completely housed within an ornamental casing and which is provided with a plurality of meshing gears which operate practically noiselessly, and which is provided with means for limiting the arcuate or rotative movement of one of the gears.

A further object of the invention is to provide an improved tilting device for Venetian blinds which comprises a plurality or train of gears, one of the gears having a pinion operating in an arcuate slot, and having means provided for creating a friction on some of the operating elements so that the position of the slats will not be changed unless positively operated by the operating cord.

Numerous other objects and advantages will be apparent throughout the progress of the following specification.

The accompanying drawing illustrates a selected embodiment of the invention and the views therein are as follows:

Fig. 1 is a detail elevation of a Venetian blind partly in section and embodying the invention.

Fig. 2 is a detail perspective view of the improved tilting device.

Fig. 3 is a longitudinal vertical sectional view on the line 3—3 of Fig. 4.

Fig. 4 is a detail sectional view on the line 4—4 of Fig. 3.

Fig. 5 is a detail plan view of the friction washer or element.

The Venetian blind herein shown for the purpose of illustration comprises an upper supporting member 5 carrying pulleys 6 over which operating cords 7 pass for raising and lowering the blind. A tilting bar 8 is positioned immediately below the upper supporting member 5, and this tilting bar has tapes 9 fastened thereto which support slats 10 in proper spaced relationship.

The tilting bar 8 is for the purpose of tilting the slats at the desired angle, the slats conforming to the angle which the tilting bar assumes.

A Venetian blind tilting device 11 is provided for tilting the tilting bar 8 and for holding the tilting bar in its tilted position. The device 11 comprises a casing or housing 12 which is made

of a casing portion 13 and a removable cover plate 14.

A wedge-shaped pulley 15 is formed with an axle 16 which is revolvably mounted in the casing 12. A pinion 17 is rigidly fixed to the pulley 15 and meshes with an idler gear 18 which is revolvably mounted on a pin 19 carried by the casing. A tilting gear 20 is provided with a thickened portion or bushing 21. A pin 22 projects outwardly from a face of the tilting gear 20 and extends through an arcuate slot 23 formed in the part 13 of the casing 12. This arcuate slot is practically one-half of a circle and permits 180° movement of the tilting gear 20. A pin or shaft 24, having a squared projection 25, removably carries the tilting gear 20. This pin or shaft 24, while removable with respect to the gear 20, is held in position and in fixed driving relationship to the gear 20 by means of a removable pin 26 which passes through the bushing or hub 21. In other words, removal of the removable pin 26 permits the gear 20 to be removed from the shaft 24. The gear 20, including the bushing or hub 21, is provided with extensions 27 on each side thereof and provides bearings for revolvably mounting the tilting gear 20. These projections or extensions 27 extend a predetermined distance through openings 28 and 29 in the casing portion 13 and cover plate 14 respectively. The squared end 25 of the shaft or pin 24 is receivable in a square opening 30 in the tilting bar 8 so that during revolvable movement of the shaft or pin 24, the tilting bar 8 will be tilted through various angles. The purpose of making the shaft or pin 24 removable is so that it can be removed from the bushing or hub 21 and inserted in the opposite side so as to make the tilting device capable for both right and left-hand operation. In the drawing the tilting device is shown mounted on the left-hand side of a Venetian blind with the squared portion extending from the right-hand side thereof. If, however, it is desired to use the same tilting device for right-hand operation, that is, with the tilting device mounted on the right-hand side of the blind, the locking pin 26 is removed and the shaft taken out so that the square part of the shaft would extend through the opening 29 in the closure plate 14 instead of the square end extending through the opening 28 in the casing portion 13. Therefore, by simply removing the screw 26 and inserting the shaft or pin 24 into the opposite side of the bushing or hub 21, the device can be converted easily from left-hand to right-hand operation, the position of the tilting gear 20 not being disturbed.

A tilting cord 31 passes over the periphery of the wedge-shaped pulley 15 and is adapted to rotate the pulley. However, the tilting bar 8 need only operate 180°, the movement of the pulley 15 being limited to a 180° movement. Therefore, when the tilting cord 31 is pulled to operate the tilting bar, the pulley will only rotate 180° in either direction. If, however, a pull is applied to the tilting cord after the full 180° movement has been made, the tilting cord will slip frictionally about the periphery of the pulley. Therefore, none of the parts can become damaged or jambed.

To assist in frictionally maintaining the blind in its tilted position, a friction element is provided. This friction element comprises a washer 32 fixed to the cover plate 14. This washer is provided with a plurality of circumferentially spaced openings or holes 33 into which a ball 34 is pressed by a spring 35. The ball 34 and spring 35 are mounted in a recess 36 formed in the pulley 15 which includes a thickened portion 37. The ball 34 is in constant engagement with the washer 32 and during rotative movement of the pulley 15, the ball 34 will click past the openings 33. However when the ball 34 is in a respective opening 33, the friction will be somewhat increased and, therefore, should there be any tendency of the slats to flatten out by wind pressure or otherwise, the straightening-out effect could not be greater than the distance between the spaced holes 33 because the ball 34 would be seated in one of the openings 33. The additional friction created by the ball 34 engaging its proper socket or opening 33, tends to frictionally hold the blind in its proper tilted position. However, operation of the cord to rotate the pulley 15 permits the ball to click past the respective openings. Normally the train of gears, including the pinion 17, the idler gear 18 and the tilting gear 20, are sufficient to prevent the blind from straightening out, but to overcome or prevent the danger of wind pressure from interfering with the tilted position of the slats, the ratchet ball 34 and washer 32 are provided. This ratchet ball 34 and washer 32 positively but resiliently hold the slats of the blind at the desired angle regardless of the wind pressure on the tilted slats.

The upper part of the casing 12 is provided with an opening 38 to permit new cords to be placed around the pulley and threaded through the casing. To assist in threading new cords, a guard 39 is fixed to a part of the casing as clearly shown in Fig. 3. This guard also assists in preventing the cord 31 from slipping off of the wedge-shaped pulley.

The cover plate 14 is fastened to its cooperating part 13 of the casing by means of screws threadedly engaging bosses 40.

Fasteners 41 may be integrally formed with the casing so that the tilting device may be fastened to the upper structure 5 by suitable fastening means, such as screws 42.

Operation

To operate the tilting bar 8 to tilt this bar and consequently the slats 10, the tilting cord 31 is operated. Movement of the tilting cord 31 causes rotation of the wedge-shaped pulley 15 which causes rotation of the tilting gear 20 through the intermediary of the idler gear 18. The rotation of the tilting gear 20, however, is limited by the pin 22 engaging the slot 23. If, however, the cord is still pulled after the pin 22 is at the end of the slot 23, the cord will merely slide over the

pulley. The rotation of the tilting gear 20 will cause rotation of the shaft or pin 24 and inasmuch as the end of the shaft or pin 24 is squared as indicated at 25, the tilting bar 8 will be moved through various angles to conform with the rotative movement of the shaft 24. 5

The invention provides a simple, attractive and efficiently operating device for operating the tilting bar of a Venetian blind. The hand operating cord on the operating pulley is so positioned 10 that it will extend forwardly a predetermined distance from the top bar of the blind, thereby permitting convenient operation. The device is provided with means for restricting the revoluble movement of the tilting bar, as it is only necessary 15 to operate the tilting bar 180° to effect positions of the slats. The device is efficient and practically noiseless in operation, contains relatively few and simple parts and can be quickly and economically manufactured and assembled. 20

Changes may be made in the form, construction and arrangement of the parts without departing from the spirit of the invention or sacrificing any of its advantages, and the right is hereby reserved to make all such changes as 25 fairly fall within the scope of the following claims.

The invention is hereby claimed as follows:

1. A tilting device for Venetian blinds comprising a tilting gear, cord operated means for rotating the tilting gear, and stop means controlled by the position of the tilting gear for limiting the rotation of said gear. 30

2. A tilting device for Venetian blinds comprising a tilting gear, cord operated means for 35 rotating the tilting gear, and means for limiting the rotation of the tilting gear, said last means comprising a slot and pin connection.

3. A Venetian blind tilting device comprising a casing, a gear revolvably mounted in said casing, 40 a rotatable pulley for rotating said gear, and means rotatably mounted in the casing and connecting said pulley and gear, said casing having an arcuate slot therein, and a pin mounted on the gear and extending through said slot for limiting the 50 revoluble movement of said gear.

4. A Venetian blind tilting device comprising a casing, a gear revolvably mounted in said casing, 45 a rotatable pulley for rotating said gear, means rotatably mounted in the casing and connecting said pulley and gear, said casing having an arcuate slot therein, and a pin mounted on the gear and extending through said slot for limiting the 50 revoluble movement of said gear.

5. A Venetian blind tilting device comprising a rotatably mounted pulley, a pinion on said pulley, a rotatably mounted tilting gear, and an idler gear connecting said tilting gear and pinion 55 whereby rotative movement of said pulley causes rotative movement of said tilting gear.

6. A Venetian blind tilting device comprising a rotatably mounted pulley, a pinion on said pulley, a rotatably mounted tilting gear, an idler 60 gear connecting said tilting gear and pinion whereby rotative movement of said pulley causes rotative movement of said tilting gear, and a casing in which said pulley, pinion, idler gear and tilting gear are mounted. 65

7. A Venetian blind tilting device comprising a rotatably mounted pulley, a pinion on said pulley, a rotatably mounted tilting gear, an idler 70 gear connecting said tilting gear and pinion whereby rotative movement of said pulley causes rotative movement of said tilting gear, a casing in which said pulley, pinion, idler gear and tilting gear are mounted, said casing having an arcuate slot therein, and a pin on said tilting gear and

engaging said slot for limiting the rotative movement of said tilting gear.

8. A Venetian blind tilting device comprising a rotatably mounted pulley, a pinion on said pulley, a rotatably mounted tilting gear, an idler gear connecting said tilting gear and pinion whereby rotative movement of said pulley causes rotative movement of said tilting gear, a casing in which said pulley, pinion, idler gear and tilting gear are mounted, said casing having an arcuate slot therein, a pin on said tilting gear and engaging said slot for limiting the rotative movement of said tilting gear, a spring pressed ball carried by said pulley, and a disk carried by said casing and adapted to have contacting relationship with said ball.

9. A Venetian blind tilting device comprising a rotatably mounted pulley, a pinion on said pulley, a rotatably mounted tilting gear, an idler gear connecting said tilting gear and pinion whereby rotative movement of said pulley causes rotative movement of said tilting gear, a casing in which said pulley, pinion, idler gear and tilting gear are mounted, said casing having an arcuate slot therein, a pin on said tilting gear and engaging said slot for limiting the rotative movement of said tilting gear, a spring pressed ball carried by said pulley, and a disk carried by said casing and adapted to have contacting relationship with said ball, said disk having a plurality of circumferential openings provided therein to receive said ball.

10. A Venetian blind tilting device comprising a casing, a revolvably mounted pulley, a tilting gear driven by said pulley, a shaft mounted in said tilting gear and adapted to be removed therefrom, said shaft extending through one side of the casing, said shaft adapted to be inserted into said tilting gear on opposite sides of said gear whereby said tilting device is adapted for either right or left-hand operation.

11. A Venetian blind tilting device comprising a casing, a revolvably mounted pulley, a tilting gear driven by said pulley, a shaft removably mounted in said tilting gear and extending through one side of the casing, said shaft adapted to be inserted into said tilting gear on opposite sides of said gear whereby said tilting device is adapted for either right or left-hand operation, a plate having sockets therein fixed to a part of said casing, and a spring pressed ball operatively carried by said pulley and adapted to have contacting relationship with said disk and with the sockets therein.

12. A Venetian blind tilting device comprising a casing, a revolvably mounted pulley, a tilting gear, a pinion on said pulley, an idler gear meshing with said pinion and said tilting gear whereby rotative movement of said pulley causes rotative movement of said tilting gear, a shaft removably mounted in said tilting gear and extending through the casing, said shaft adapted to be inserted into said tilting gear on opposite sides thereof whereby said tilting device is adapted to be mounted on either the right or the

left-hand side of a Venetian blind, and means for limiting the rotative movement of said tilting gear.

13. A Venetian blind tilting device comprising a casing, a revolvably mounted pulley, a tilting gear, a pinion on said pulley, an idler gear meshing with said pinion and said tilting gear whereby rotative movement of said pulley causes rotative movement of said tilting gear, a shaft removably mounted in said tilting gear and extending through the casing, said shaft adapted to be inserted into said tilting gear on opposite sides thereof whereby said tilting device is adapted to be mounted on either the right or the left-hand side of a Venetian blind, and friction means carried by said pulley and casing.

14. A Venetian blind tilting device comprising a casing, a revolvably mounted pulley, a tilting gear, a pinion on said pulley, an idler gear meshing with said pinion and said tilting gear whereby rotative movement of said pulley causes rotative movement of said tilting gear, a shaft removably mounted in said tilting gear and extending through the casing, said shaft adapted to be inserted into said tilting gear on opposite sides thereof whereby said tilting device is adapted to be mounted on either the right or the left-hand side of a Venetian blind, and friction means, carried by said pulley and casing, said friction means comprising a spring pressed ball and a socketed plate.

15. A Venetian blind tilting device comprising a casing, a revolvably mounted pulley, a tilting gear, a pinion on said pulley, an idler gear meshing with said pinion and said tilting gear whereby rotative movement of said pulley causes rotative movement of said tilting gear, a shaft removably mounted in said tilting gear and extending through the casing, said shaft adapted to be inserted into said tilting gear on opposite sides thereof whereby said tilting device is adapted to be mounted on either the right or the left-hand side of a Venetian blind, and friction means carried by said pulley and casing, said friction means comprising a spring pressed ball and a socketed plate, said means for limiting the rotation of the tilting gear comprising an arcuate slot in the casing, and a pin on the tilting gear engaging said arcuate slot.

16. A tilting device for Venetian blinds comprising a tilting element, cord operated means for rotating the tilting element, and stop means controlled by the cord operated means for limiting the rotation of the said tilting element.

17. A tilting device for Venetian blinds comprising a casing, a revolvably mounted member, a revolvable tilting element driven by said member, a shaft operated by said tilting element and adapted to extend through one side of the casing, said shaft also being adapted to be reversed in the casing to extend through the opposite side of the casing whereby said device is adapted for either right or left hand operation.
